UNITED STATES PATENT OFFICE.

ALFRED DAY, OF PHILADELPHIA, PENNSYLVANIA.

EXERCISER.

No. 897,722.

Specification of Letters Patent.

Patented Sept. 1, 1908.

Application filed May 4, 1908. Serial No. 430,668.

To all whom it may concern:

Be it known that I, ALFRED DAY, a citizen of the United States, residing at Philadelphia, county of Philadelphia, State of Pennsylvania, have invented a new and useful Exerciser, of which the following is a specification.

My invention relates to a new and useful exercising device and consists of a frame 10 having a plurality of rollers rotatably or stationarily mounted thereon and so supported that any one can be removed and replaced, independently of the others.

It further consists of a new and novel 15 roller.

It further consists of other novel features of construction, all as will be hereinafter fully set forth.

Figure 1 represents a side elevation of an 20 exercising device embodying my invention. Fig. 2 represents an end view thereof. Fig. 3 represents a partial sectional view and partial elevation of a portion of the device in detached position. Fig. 4 represents a sectional view of one of the rollers.

I have found that in exercising devices it is necessary to mount the rollers so that they will rotate freely but will be laterally stationary and that the rollers are so mounted 30 that they can be independently removed and replaced.

In the drawings, I have shown a construction for carrying out my invention but it will be evident that changes may be made 35 therein and other instrumentalities may be employed which will come within the scope of my invention and I do not therefore desire to be limited in every instance to the exact construction as herein shown and described but desire to make such changes as 40 may be necessary.

Similar numerals of reference indicate corresponding parts in the figures.

Referring to the drawings, 1 designates 45 the frame of the exercising device and consists of the front and rear uprights 2 connected by the lower side pieces 3 and the upper side pieces 4 and by cross bars 5 forming a firm and substantial frame which is prefer- 50 ably mounted upon rollers 6, it being noted that the front cross bar 5 is connected with the front uprights 2 at a higher point than that of the rear cross bar 5 with the rear up- rights 2.

55 7 and 8 designate strips which are provided with recesses 9 at suitable points adapted to

embrace or receive the cross bars 5, said recesses being situated at the front and rear portions of said strips for this purpose.

10 designates set screws which pass 60 through suitable openings in the strips 7 and 8 and are adapted to be tightened against the cross bars 5 for firmly locking the strips 7 and 8 in position.

11 designates a plurality of slots formed in 65 the upper face of said strips 7 and 8 and which extend at an angle and are suitably situated in order to provide journals for the rollers.

The rollers are preferably formed with the 70 body portion 12 of wood which is cut away a portion of its length forming a shoulder 13 and around the cut-away portion is placed the rubber 14 which abuts said shoulder 13 said rubber 14 terminating a suitable dis- 75 tance from the end of the body 12, which end is adapted to receive a sleeve 15 which firmly locks the rubber 14 in position, it being noted that the enlarged portion of the body 12, the rubber 14 and the sleeve 15 80 form a roller, of equal diameter, which prevents injury to the feet of the user.

Seated in suitable openings at opposite ends of the roller are the pins 16 which project a suitable distance and are adapted to 85 be seated in the angular slots 11 of the strips 7 and 8, whereby it will be seen that the rollers are permitted to freely rotate but lateral movement thereof is prevented, it being noted that the ends of the body portion 12 90 are situated preferably close to the inner wall of the strips 7 and 8 to prevent improper movement of the roller.

By the construction just above described it will be seen that the user steps upon the 95 rollers and by grasping the upper bar 4 can steady himself and immediately start the action of running, which is permitted by rotation of the rollers while injury, as above stated, is prevented by reason of the rubber 100 facing of the rollers. At the same time, as will be understood from Fig. 3, should anything occur to any one of the rollers it can be quickly removed from its slots 11 and replaced by a new one without disturbing any 105 of the other rollers.

Having thus described my invention, what I claim as new, and desire to secure by Letters Patent, is:—

1. In a device of the character described, a 110 movable rigid frame, strips situated at an incline upon said frame, and having a plurality

of slots extending in said strips and rollers having ends seated in said slots, the upper wall of each slot extending over the end of the roller therein, whereby the same are prevented from accidental displacement.

2. In a device of the character described, a frame, strips situated at an angle upon said frame and having a plurality of slots inclined to the plane of the strips, means for locking 10 said strips in position, and rollers having a portion thereof seated in said slots, whereby

said rollers may be rotated but are prevented from lateral movement.

3. In a roller for an exercising device, a body portion, a shoulder thereon, rubber 15 abutting said shoulder, a sleeve adapted to hold said rubber in position, and pins projecting from the ends of said roller:

ALFRED DAY.
